UNITED STATES PATENT OFFICE.

THOMAS J. KEHOE, OF DAYTON, OHIO.

RADIATOR.

No. 895,767.

Specification of Letters Patent.

Patented Aug. 11, 1908.

Application filed April 5, 1906. Serial No. 309,990.

To all whom it may concern:

Be it known that I, THOMAS J. KEHOE, a citizen of the United States of America, and resident of Dayton, in the county of Montgomery and State of Ohio, have invented certain new and useful Improvements in Radiators, of which the following is a specification.

This invention relates to improvements in radiators of that class used in connection with automobiles for reducing the temperature of water ordinarily employed for cooling engine cylinders; and the object thereof is to afford a device of the class described which will be highly efficient and durable.

15 The object of this improvement is accomplished by the construction illustrated in the accompanying drawings, in which:

Figure 1. is a rear elevation of the radiator with a part thereof broken away; Fig. 2. is 20 a cross section of the same on the line $x-x$ of Fig. 1; Fig. 3. is a detail showing a portion of one of the radiating sections and also a portion of the adjacent tank; Fig. 4. is a detail showing a sectional view of a portion of one 25 of the radiating plates; Fig. 5. is a similar view showing a modified form of radiating plate; and Fig. 6. is a detail in perspective showing a portion of one of the radiating sections.

30 Similar numerals of reference indicate corresponding parts throughout the several views, and referring now to the same: 1 and 2 are upper and lower tanks respectively which are connected at their ends by standards 3, each of the latter having a side bracket 4 by means of which the device is mounted in place upon the frame of the automobile or other foundation. The tanks 1 and 2 each have a pipe 5 leading thereto for 35 suitable connection with the water circulating system of the engine or other contrivance.

A multiplicity of flat hollow sections 6 are arranged between the upper and lower tanks, 40 and each section is connected at its respective ends with the adjacent tanks and affords communication therethrough from one tank to the other. The said sections are each formed with a lap seam 6' at its respective 45 edges, which afford reinforcement.

Upon each side of each section 6 is secured a radiating plate 7 from the outer face of which protrudes numerous tongues 8. The tongues are formed by cutting through the 50 plate and pressing a portion thereof outward

from the general plane of its surface, but without severing the inner end of the tongue from the body of the plate, thus leaving an opening 9 in the plate beneath each tongue.

The plates 7 are united to the sides of the sections 6 respectively by means of solder so that they thereby become as an integral part thereof, and with the tongues 8 protruding outwardly. In the tank 2 is arranged a pipe 10 which has communication with the corresponding pipe 5 which leads from said tank. A number of perforations 11 are made in the pipe 10 at points coincident with the lower ends of the respective sections 6; and a similar pipe 12 (shown in dotted lines) is arranged in the tank 1 and communicates with the corresponding pipe 5. The object of the pipes 10 and 12 is to afford a uniform flow of water through the various sections.

The tank 1 has a cap 13 at its top which, 75 when removed, affords an opening for filling the radiator with water; and the tank 2 has a screw plug 14 in its bottom which, when removed, affords an opening for drainage.

In Fig. 5. of the drawings is shown a modified form of radiating plate. In this form the plate is similar to that in the former instance in all respects except that those portions 15 which intervene between the tongues 16 are arched outwardly so as to project from 80 the side of the section to which the plate is attached.

In the operation of this invention the tanks 1 and 2 are connected by means of the pipes 5 with the corresponding pipes of the water 90 circulating system as above described, and as the heated water passes through the sections 6 from one tank to the other because of gravitation (or other force as the case may be), the heat of the water will be more or less drawn 95 therefrom by direct contact with the sections 6, and by convection afforded by the tongues 8, into the open spaces between the sections. Air of lower temperature than the water contained in the sections is caused to pass naturally or by force between the various sections, and in so passing absorbs the heat drawn from the water within the sections by the metallic tongues, and furthermore carries away the heat induced by radiation from the 100 external surfaces of the sections and plates. Thus water in passing through the sections is deprived of its contained heat by the circulation of air assisted by the processes of both 105 radiation and convection.

Having described my invention what I claim as new and desire to secure by Letters Patent, is:

1. In a radiator having parallel hollow sections, a series of plates each of which has numerous protruded tongues on one of its sides, said plates being secured respectively with their flat sides against the corresponding sides of said sections.
- 10 2. In a radiator having parallel hollow sections, a series of plates each of which has nu-

merous protruded tongues on one of its sides, the outer ends of said tongues being bent at an angle, said plates being secured respectively with their flat sides against the corresponding sides of said sections. 15

In testimony whereof I affix my signature, in presence of two witnesses.

THOMAS J. KEHOE.
